CLAIM

The ornamental design for a stand for wrist-worn electronic device, as shown and described.

DESCRIPTION

FIG. 1 is a front perspective view of a stand, having a supporting member and an electronic device holder, for wrist-worn electronic device showing my new design;

FIG. 2 is a rear perspective view thereof;

FIG. 3 is a front elevational view thereof;

FIG. 4 a rear elevational view thereof;

FIG. 5 is a left side elevational view thereof; and

FIG. 6 is a right side elevational view thereof;

FIG. 7 is a top plan view thereof;

FIG. 8 is a bottom plan view thereof;

FIG. 9 is a front perspective view of the supporting member;

FIG. 10 is a rear perspective view of the supporting member;

FIG. 11 is a front perspective view of the electronic device holder;

FIG. 12 is a rear perspective view of the electronic device holder;

FIG. 13 is a front perspective view of the stand for wrist-worn electronic device in which the supporting member and the electronic device holder are shown separated for clarity of disclosure; and,

FIG. 14 is a rear perspective view of the stand for wrist worn electronic device in which the supporting member and the electronic device holder are shown separated for clarity of disclosure.

The broken lines illustrate portions of the stand for wrist-worn electronic device in which the design is embodied that
